UNITED STATES PATENT OFFICE.

GEORGE G. BATES, OF NEW YORK, N. Y.

DESIGN FOR A WAIST-BELT.

Specification forming part of Design No. 7,791, dated October 13, 1874; application filed September 22, 1874.
[Term of Patent 7 years.]

To all whom it may concern:

Be it known that I, GEORGE G. BATES, of New York, in the county and State of New York, have invented a Design for a Belt, of which the following is a specification:

The nature of my design is fully represented in the accompanying drawing, in which—

Figure 1 is a perspective view of a belt made according to my invention. Fig. 2 is a partial longitudinal section. Fig. 3 is a transverse section.

The belt has the central longitudinal portion fluted transversely, in the form shown at *a* in Figs. 1 and 2, and the portion near the edges flattened, as shown at *b* in Figs. 1 and 3.

I claim as my invention—

The design for a belt, substantially as described and shown.

GEO. G. BATES.
